UNITED STATES PATENT OFFICE

JOHN S. THURMAN, OF ST. LOUIS, MISSOURI.

VACUUM CLEANING-TOOL.

986,245.

Specification of Letters Patent. Patented Mar. 7, 1911.

Application filed May 5, 1910. Serial No. 559,488.

To all whom it may concern:

Be it known that I, JOHN S. THURMAN, citizen of the United States, residing at St. Louis, State of Missouri, have invented certain new and useful Improvements in Vacuum Cleaning-Tools, of which the following is a full, clear, and exact description, reference being had to the accompanying drawings, forming a part hereof.

10 My invention has relation to improvements in suction-heads or cleaning tools for vacuum cleaning systems; and it consists in the novel details of construction more fully set forth in the specification and pointed out 15 in the claims.

In the drawings, Figure 1 is a perspective of a row of books showing my invention applied thereto; Fig. 2 is a side view of two books of unequal height showing the tool 20 applied with its narrow edge to the shorter book; Fig. 3 is a plan of the tool; Fig. 4 is an edge view thereof; Fig. 5 is an enlarged cross section on the zig-zag line 5—5 of Fig. 3; Fig. 6 is a cross-section on the line 6—6 25 of Fig. 3; Fig. 7 is a cross section on the line 7—7 of Fig. 3; and Fig. 8 is a side elevation of a desk showing the application of a modified form of tool to the floor on which the desk rests.

30 The present invention finds special application in libraries where occasion arises to remove dust which has accumulated on the edges of the leaves, collectively forming the top of the book in the position usually occupied by the latter on a shelf or in a book case, the tool herein being particularly designed to operate on different widths and heights of books placed side by side on such shelf. Obviously too, the tool may be employed for other purposes as clearly apparent from a detailed description of the invention, which is as follows:—

Referring to the drawings, II represents a 45 hose or air-line leading to any suitable vacuum pump or exhauster (not shown), the free end of the hose being passed over or otherwise secured to the cylindrical stem *a* of the suction-head, the body portion *b* of which is in the form of a long flattened tube closed at 50 the end. The part *b* is therefore adapted to present a flat face and a narrow edge or face to the surface of the book or other article to be cleaned as clearly obvious from the drawings. Adjacent to the closed end of the tool, 55 and in one of the flat or broad faces is formed an air-intake opening *o*, and at a

point contiguous and interior thereto and in one of the narrow edges is formed an intake opening *o'* of necessarily somewhat smaller area.

As a rule books placed on a library shelf S, are neither uniform in height or thickness, and in order to take up the dust from the tops thereof requires the application of suction-tools of different dimensions, or, if a single tool be used, of a nozzle which will operate on the smallest book of the series in which event too much time is consumed in passing such a small nozzle over a large book. With my improved tool, the flat face 70 of the body portion *b* in which is formed the intake opening *o* is passed back and forth over the tops of the larger books B, after which the tool may be inserted the narrow way between two books to reach the top of a shorter and thinner book B'. In that case the small opening *o'* is brought into requisition, the vacuum in the tool drawing in the dust-laden air through said latter opening into the tool and through the hose II whence 80 it passes into a suitable dust receptacle (not shown) as well understood in the art.

A practical tool for library use averages eighteen inches in length (the body *b* twelve inches, and stem *a* six inches), with the flat 85 or broad face of the body one and one-quarter inches in width, and the narrow edge approximating three-eighths of an inch. The opening *o* is about one by one-half inch, and the opening *o'* one-quarter by three-sixteenths. Of course, these proportions may be varied according to the size of tool, it being at all times desirable that the tool shall have a long reach. Although preferably straight, when serving as a library-tool, it is apparent 95 that for some purposes a curvature might be given the tool to reach out of the way places as for example, the floor under a desk D, the rollers or supporting casters of which hold the desk a fraction of an inch above 100 the floor. Such curved tool *a'*, *b'*, is illustrated in Fig. 8.

As the tool is passed with its narrow edge over the shorter and narrower book B', the broad or flat face necessarily contacts more 105 or less against the side of a larger book B, such contact closing to a greater or less degree the opening *o*, thereby constraining the current to pass mainly through the opening *o'*. In that way the small book is cleaned of 110 its dust as effectively as the large book. Thus by a mere rotation of the tool about

its axis through an angle of ninety degrees to present either the broad face or its narrow edge to the surface of the particular article to be cleaned, the dust may be removed from any surface on which it has accumulated.

The tool is essentially a long flattened tube closed at one end with intake openings disposed in contiguous faces adjacent to such end.

Having described my invention, what I claim is:

1. A vacuum-cleaning tool comprising a long flattened tube closed at one end and having an intake opening in the broad side or face confined to a position adjacent to the

closed end and with a second intake opening in the narrow side.

2. A vacuum-cleaning tool comprising a long flattened tube closed at one end and having an intake opening in the broad side or face confined to a position adjacent to the closed end, and with a second intake opening in the narrow side out of alignment with the first opening.

In testimony whereof I affix my signature, in presence of two witnesses.

JOHN S. THURMAN.
